UNITED STATES PATENT OFFICE.

FRED S. CARVER, OF EAST ORANGE, NEW JERSEY.

AUTOMATIC PRESS.

Application filed December 22, 1920. Serial No. 432,440.

To all whom it may concern:

Be it known that I, FRED S. CARVER, a citizen of the United States, and a resident of East Orange, county of Essex, and State of New Jersey, have invented certain new and useful improvements in Automatic Presses, of which the following is a specification.

My invention relates to a press for expressing fluids from material which is partly liquid and partly solid, and forming a cake of the solid material.

While the invention is capable of various applications, it will be described herein in connection with a cocoa press of the general type manufactured by European manufacturers and imported into this country, in which ground cocoa bean material is subjected to hydraulic pressure to separate the liquid cocoa-butter, so-called from the solid cocoa which is formed into a hard cake.

The ground cocoa bean material is placed in pots and the liquor is expressed through filter pads. Before the pressure is applied to the ground cocoa bean material to express the liquor, it is necessary that the pots be closed tight so that there is no outlet for the fluid except through the filter pads.

The closing of the pots has heretofore been accomplished by a workman manually operating a screw and wedge arrangement for each pot, which has to be screwed up after the pots are in place and before the pressing operation is commenced, and unscrewed again after the pressing operation is completed.

The principal object of my invention is the provision of a press which can be easily and simply operated and in which the power supplied for the pressing operation is made use of preliminarily to the pressing operation for automatically closing the press pots, the closing of the press pots being automatically accomplished prior to the application of such power for the pressing operation and same being automatically opened after the pressing operation is completed. The closing of the press pots prior to pressing and the opening of the press pots after the pressing operation is completed is performed automatically and no attention thereto is required on the part of the press operator. Further objects of my invention subordinate to such principal object will

appear in the course of the following description. 55

In the drawings forming a part of this specification, and showing an embodiment of the invention for the purpose of illustration and for affording an understanding of 60 the invention and not for limitation thereof, Fig. 1 is a side view of a cocoa press with parts broken away. Fig. 2 is a horizontal sectional view taken substantially on the broken line 2—2, Fig. 3. Figs. 3 and 4 65 are vertical sectional views taken substantially on the broken line 3, 4—3, 4, Fig. 2, and showing the press pots in two different positions.

Fig. 5 is a plan view and Figs. 6 and 7 70 are vertical sectional views of a modified form of construction, the sectional part of Fig. 5 being taken on the line 5—5, Fig. 6.

In the press shown for illustration reference character 10 designates the base of the 75 press, which contains the hydraulic piston 11, and 12 the press head which is connected to the base 10 by the four posts 13.

The press pots 14 are provided with side lugs 15 which run in runways 16 in the 80 brackets 17, bolted to the base 10 and head 12. The press pots 14 are preferably constructed in accordance with my Patent No. 1,247,078 dated Nov. 20th, 1917, and have the upper portions 18 of their otherwise substantially cylindrical inner walls enlarged 85 somewhat to permit the ready removal of the cake of cocoa 19 formed therein during the pressing operation. The press pots 14 have an inwardly extending bottom flange 90 or lip 20 for supporting the piston 21 which forms a movable bottom for the press pot.

Between the brackets 17, 17 slidably mounted on the posts 13, 13 are a series of platens 22 which are provided on their 95 upper sides with plungers 23 for actuating the pot pistons 21. Platens 22 are supported on the ledges 24, 24 formed on the brackets or frames 17, the two ledges 24 of each pair of ledges in the series being separated 100 a greater distance than the ledges of the next lower pair, so that, while the platens 22 can move upwardly freely, each thereof stops at its proper position during downward movement.

In the construction shown in Figs. 1—4 each of the platens 22 carries a pair of runway members 25 provided with runways

26 which when the platen is in the position supported by its supporting ledges 24, 24 are in line with the corresponding runways 16 in the brackets 17. Thus the pots 14 can be freely pushed in and out from the runways 16 to the runways 26 and vice versa.

In order to secure alignment between the runways, the members 25 are adjustably mounted on the platen 22, and in order to permit relative movement between the members 25 and the platens 22 on which the members 25 are supported, springs are interposed between platens 22 and the members 25 borne thereby. In the form shown in Figs. 1 to 4, bolts 27 having their heads 28 received in the bores 29 of the members 25 are screwed into collars 30 in platens 22 and the telescopic connection thus made up, comprising the bolt 27 and sleeve 25' of the member 25, is surrounded by the expansion spring 31, which is normally under a considerable tension. The bores 29 of the members 25 have a stop lip or flange 32 at their lower ends. The bolts 27 are held from turning by means of pins or dowels 34 running in the key slots 35 and the collars 30 are held in adjusted position by means of set screws 36.

30 The normal position of the runway members 25 is shown in Fig. 3, the member 25 being supported with its runway 26 in line with the corresponding runway 16 by the spring 31 controlled by the bolt 27.

35 It will be apparent that when platen 22 is moved upwardly the upward movement thereof is communicated to the pot 14 supported thereabove by springs 31 and the pot is moved upwardly until it comes into contact with and is stopped by the cover or closure member 37 on the platen 22 on the lower face of platen 22 next above in the series, or in the case of the uppermost pot, on the press head 12. After all the 40 pots are closed in this manner the plunger 23 of the platen 22 comes into contact with pot piston 21 and forces it upwardly, expressing the liquid material and forming the cake 19 of solid cocoa within the pot, the bolt 27 and the sleeve 25' of the member 25 telescoping upon one another and the spring 31 being compressed as shown in Fig. 4. Upon downward movement of 45 the press piston 11, after the pressing operation is completed, the plungers 23 retreat from the press pots 14 and the relative lifting of the latter by the expanding action of springs 31 being limited by bolts 27, the parts are restored to the position 50 shown in Fig. 3, thereby automatically opening up the press pots, so that they can be drawn out upon their runways 16 and the cakes of solid cocoa 19 removed therefrom, it being understood that as the platens 55 22 move downward each thereof is stopped

upon reaching its respective supporting ledges 24, 24.

The modified construction of Figs. 5, 6 and 7 differs from that described, in two principal respects. The runways 26 are 70 replaced by supporting tracks 26^a depending from the lower sides of platens 22^a and permitting free upward movement of pots 14 and ledges 15 relative thereto. A ring 25^a on the top of the platen surrounds the 75 platen plunger 23^a and is pressed upward by springs 31^a and its upward movement under the action of said springs is limited or controlled by adjustable bolts 27^a adapted to telescope into the ring 25^a. 80

With this arrangement it will be seen that the preliminary upward movement of the press pots to close or seal the same is accomplished through the action of the spring supporting the ring 25^a acting upon the bottom of the press pot, and that the runways for supporting the press pot in the in or pressing position are separate from the ring 25^a which has the function of preliminarily raising the press pot to 90 close the same. In other words, the platens are provided with runways or guides for the press pot which comes underneath the same and is closed thereby, and the spring means for the preliminary closing of the 95 press pots is on top of the platen and is applied to the pot next above the platen in the series. With this construction the preliminary pot closing pressure is applied uniformly about the margin of the pot 100 and the manufacture and assembly are extremely simple. With the differences noted, the operation of the press is the same as described in connection with the form shown in Figs. 1 to 4. 105

As already stated, my invention has various applications and I do not desire to be limited by the particular embodiments described and shown, and numerous changes and modifications may be resorted to within 110 the scope of my claims and without departing from the principle of my invention.

I claim:

1. In a press, a pot, means for applying pressure to the contents of the pot, and means for automatically closing the pot prior to the application of pressure to its contents. 115

2. In a press, a pot, means for applying pressure to the contents of the pot, and means operated from the first named means for automatically closing the pot prior to the application of pressure to its contents. 120

3. In a press, a pot, means for applying pressure to the contents of the pot, and means operated from and yieldably connected to the first named means for moving the pot against a closure prior to the application of pressure to its contents. 125

4. In a press, a pot, means for applying 130

pressure to the contents of the pot from beneath, and yieldable means connected with the first named means and adapted to yieldably force the pot against a closure prior to the application of pressure to its contents.

5. In a press, a pot, a plunger adapted to apply pressure to the contents of the pot, a yieldable support for the pot partaking of the movement of said plunger, and adapted 10 to move the pot against a closure prior to the application of pressure to the contents of the pot by such plunger.

6. In a press, a pot, a plunger adapted to apply pressure to the contents of the pot, 15 spring means for lifting said pot connected to move with said plunger, and a closure for said pot located thereabove, whereby upon upward movement of the plunger the pot is yieldably forced against the closure prior to 20 the application of pressure by the plunger to the contents of the pot.

7. In a press, a series of pots, a series of 25 platens provided with closures for pots and with plungers adapted to apply pressure to the contents of the pot and located between the pots, a series of telescopic spring supported members connected to move with said platens, whereby the pots are yieldably forced against the closures prior to the application of pressure by the plungers to the contents of the pots.

8. In a press, a pressure piston and an opposing head, a series of slidably mounted platens between said piston and head, said 35 platens having runways for the reception of press pots and being provided on their lower faces with closure means, and means on said platens for yieldably raising pots thereabove, whereby when the piston is moved toward the head the pots are first forced against the 40 closures prior to application of pressure to the contents of the pots.

9. In a press, a press piston and a press head opposed thereto, a series of platens 45 slidably mounted between said piston and head, each of said platens being provided with a plunger on its upper side and a closure for a press pot on its lower side, and said platens being provided with runways for supporting press pots therebetween, said 50 plungers being adapted to apply pressure to the contents of the press pots, and springs interposed between said plungers and press pots for yieldably forcing said press pots against the closures located thereabove, prior 55 to application of pressure to the contents of the pot by means of said plungers.

10. In a press, a press piston and a press head opposed thereto, a series of platens 60 slidably mounted therebetween, and means for selectively stopping the downward movement of said platens in spaced relation to one another, said platens being provided with runways for press pots, stationary runways for press pots opposite said runways 65

on the platens when the latter are so stopped and supported, plungers on top of each of said platens and pot closures on the lower sides thereof, and telescopic spring pot raising means upon the platens whereby upon 70 upward movement of the press piston the pots on the platen runways are yieldably forced upwardly against their closures prior to application of pressure to the contents of the pots by means of the plungers.

11. In a press, a piston, an opposing press head, a plurality of slidable platens therebetween, means for supporting said platens in spaced apart relation, for the insertion therebetween and removal therefrom of 80 press containers for partly solid and partly liquid material from which the liquid material is to be expressed leaving a cake of solid material, and spring means on said platens for bodily moving said containers 85 and adapted when the press piston is actuated to force said containers against the adjacent platen or press head and to seal same prior to the application of pressure to the contents of the containers.

12. In a press, a piston, an opposing press head, a plurality of slidable platens therebetween, means for normally supporting said platens in spaced apart relation, tracks beneath the platens for receiving and temporarily supporting press containers for partly solid and partly liquid material from which the liquid is to be expressed leaving a cake of solid material, spring supported members on top of the platens and adapted 100 to contact with press containers thereabove at substantially the margin thereof, whereby when the press piston is raised the containers are forced against the platen or press head thereabove to seal the containers prior to 105 the application of pressure to contents of the containers.

13. In a press, a press piston and an opposing head, a series of slidably mounted platens between said piston and head, said 110 platens having closures in their lower faces for press pots, runways for press pots fixed to said platens beneath the same, and means on said platens for yieldably raising pots thereabove and forcing the pots against the 115 closures prior to application of pressure to the contents of the pots.

14. In a press, a press piston and a press head opposed thereto, a series of platens slidably mounted between said piston and head, each of said platens being provided with a plunger on its upper side and a closure for a press pot on its lower side, and said platens being also provided on their lower sides with integrally formed runways 120 for supporting press pots therebetween, said plungers being adapted to apply pressure to the contents of the press pots, and springs interposed between said plungers and press pots for yieldably forcing said press pots 125

4
against the closures located thereabove, prior to application of pressure to the contents of the pot by means of said plungers.

15. In a press, a pot, means for applying direct pressure to the contents of the pot from beneath, and yieldable means connected with the first named means constructed to apply substantially uniform pressure around the periphery of the pot to force the pot against a closure prior to the application of the direct pressure to its contents.

16. In a press, a plurality of pots, means for applying pressure to the contents of

said pots, comprising a corresponding plurality of movable members, and a plurality of stops for maintaining said members in relatively different normal positions.

17. In a press, a plurality of pots, means for applying pressure to the contents of said pots, comprising a corresponding plurality of movable platens, and a plurality of stops out of alignment relatively to each other for normally maintaining the platens in relatively different positions.

In testimony that I claim the foregoing, I have signed my name hereto.

FRED S. CARVER.
